UNITED STATES PATENT OFFICE.

BENJAMIN C. VANDUZEN, OF CINCINNATI, OHIO.

HYDRANT.

SPECIFICATION forming part of Letters Patent No. 295,600, dated March 25, 1884.

Application filed July 18, 1882. (No model.)

To all whom it may concern:

Be it known that I, B. C. VANDUZEN, of Cincinnati, Hamilton county, Ohio, have invented certain new and useful Improvements 10 in Hydrants, of which the following is a specification.

The object of my invention is to provide a hydrant from which the valve may be easily removed, and in which the pressure of the 15 water tends to keep the valve closed. In most of the hydrants now in use the valve has a flat seat, and the pressure of the water has a constant tendency to open the valve, for which reason the hydrant is very apt to leak.

15 My invention provides a cylindrical packing for the valve, and the tendency of the pressure of the water is to constantly prevent the valve from opening. Besides the feature relating to the valve, my invention also has a 20 reference to a novel construction and arrangement for operating the valve.

Referring to the drawings forming part of this specification, Figure 1 is an elevation of a 25 hydrant constructed according to the principle of my invention. Fig. 2 is a central vertical section of the same, also showing the valve and its connections and surroundings. Fig. 3 represents a horizontal section taken at the line $x-x$ of Fig. 1. Fig. 4 represents a horizontal section taken at the line $y-y$ of Fig. 1. Fig. 5, Sheet 2, represents a vertical central section of a modification of the pump shown 30 on Sheet 1.

A represents the casing or body of the hydrant, which may be ornamented as desired. On the upper end of this body is a cap, A', resting upon a collar or flange, a, projecting from the body A. This cap A' is capable of 35 being turned around the upper end of the body, and for this purpose is provided with a suitable handle, a', which may be located, as shown, on top of the cap, or, if preferred, it may be attached at one side of the cap. The cap A' is held in position on the body A by 40 suitable means—as, for example, by pins B, which are screwed through the cap into the body, the ends of these screws entering horizontal slots b, which construction permits the cap to be turned on the body, but prevents it 45 from rising thereon until the pins are removed.

Within the body A is located the discharge-

pipe C, to the upper end of which is attached the spout C'. The upper end of the body A is provided with the vertical slots D D', in 55 the first of which rests the spout, and in the other slot, D', extends lug d, projecting from the inner end of the spout. These slots D D' are both open at the top, to permit the spout and its attachments to be lifted out; but by 60 these slots the discharge pipe and spout are prevented from turning in the body.

In the cap A' is formed an inclined slot, E, the lower end of which is continuous with a vertical slot, E', which latter extends to the 65 lower edge of the cap, as shown in Fig. 1.

Through the inclined slot E passes the spout C. When the cap A' is turned, the lower edge of the inclined slot is pushed under the spout C', causing it and the discharge-pipe thereto 70 connected to be raised, and when the cap is turned in the opposite direction the upper edge of the slot crowds the spout down. Thus it will be seen that by turning the cap A' the discharge pipe and spout are caused to be 75 raised and lowered, and that the spout always remains in the same vertical line, never being turned to either side. A flange, e, is formed around the spout within the body, which prevents the ingress of any dirt through the slot 80 D. Another flange, e', is also formed around the lug d, and these flanges e e', fitting against the interior of the upper part of the body A, prevent any lateral movement of the discharge-pipe as it is raised and lowered, and thus the 85 valve connected to the lower end of the discharge-pipe is always moved in a vertical line, and the valve is thus not subjected to a greater wear on one side than another.

To the lower end of the body A is preferably connected a pipe, as F, to the lower end of which is connected the valve-box F', within which is located the valve G, connected to the lower end of the discharge-pipe C. The valve-box F' consists of a flared upper end, f, 90 making a chamber, f², and a chamber, f', located at its lower end, the two being separated by a constricted portion or neck, f¹, the latter forming the cylinder within which works the piston-valve G. This valve G consists of a body, g, surrounded by two annular packing-rings, h h', the two being separated by a sleeve, g', the two packing-rings and the sleeve being held on the body g by a nut, g². The diam- 95 100

ter of the packing-rings h h' is such that they will fit tightly in the neck f^2 of the valve-box; but the sleeve g' is of slightly less diameter than this neck, as shown in Fig. 2. The body 5 g of the valve is made hollow—that is, has a chamber, Z —and its lower end is provided, just above the packing h , with a series of openings, k , and the sleeve g' is also provided with a series of openings, l , corresponding in position to the openings k . These openings are so situated that when the valve is lowered they will establish a communication between the chamber f' of the valve-box and the interior of the valve, and any water entering this valve 10 may escape through the discharge-pipe C and out through the spout C' .

At one side of the chamber f' is the connection K , to which is connected the inlet-pipe which communicates with the water-supply- 20 reservoir main. A collar or flange, n , surrounds the upper part of the body g of the valve, which collar, when the valve is lowered, fits into the flared upper portion, f , of the valve-box, and prevents the valve from going 25 too far down. This ring n and the flared portion f may be ground together, and the ring n serves not only as a stop, but as a valve to prevent the water leaking into the waste while 30 communication is established between the supply and discharge pipe, and this use of the ring n as a valve would be particularly valuable should the upper packing-ring, h , leak. When the valve is lowered, as shown in Fig. 2, water entering the chamber f' passes 35 through the openings l and k , and out through the discharge pipe and spout. The packing-ring h prevents any passage of water around the valve. When, now, it is desired to stop the flow of water, the cap A' is turned, and the 40 discharge pipe and valve are thus raised, and the valve G is raised, so that the packing h is raised above the neck f^2 and the packing h' enters the lower end of the neck, which prevents any water from entering the valve. The 45 distance between the packing-rings h and h' is such that one will enter the neck before the other leaves it, which prevents any leakage of water, causing all the water which enters the valve-box F' to pass through the valve. When 50 the water is shut off, the discharge-pipe C will be full of water, and it is necessary in winter that this water should not be allowed to remain in the pipe, and by the construction above described this water is allowed to waste 55 before it can freeze. As the packing h is above the neck f^2 , and as there is a slight space between the sleeve g' and the neck f^2 , the water in the discharge-pipe C is allowed to pass backward through the openings k l , and, passing 60 up, flows out through the opening m in the pipe F , which opening is usually below the piston. In a warm climate or in the summer this wasting is not necessary, and the hole m may, if desired, be closed. When the water 65 is shut off, the head of water presses against the lower end of the valve and tends to keep

it closed, and for this reason the hydrant is not liable to leak and drip.

A valve constructed upon the above-described principles may be advantageously employed as a cut-off valve for governing the flow of water through the pipe leading from the water-main to the house, or it may be used in any other pipe through which the fluid passes. If, from any cause, the valve gets out of repair, 70 it is a very easy matter to remove it from the hydrant, the only thing necessary to be removed being the screws B , and when they are removed the cap A' may be removed, and the spout, discharge-pipe, and valve may then be 75 lifted from the hydrant. The construction of the valve and its box or chamber is such that it possesses the advantageous capability of being easily and quickly removed without change directly from the hydrant for repairs, cleaning, &c., even when the mechanism employed for reciprocating it be other than that specifically described herein.

Various modifications of the pump shown on Sheet 1 of the drawings may be made and 80 be included under one or more features of my invention.

Among the obvious modifications which can be made in the construction of the means for reciprocating the discharge-pipe, the following 85 is one of the most simple:

In Fig. 5, Sheet 2, the discharge-pipe is extended through the top of the cap A' , and is then provided with the spout C' . The cap A' is on the outside of the upper portion of the standard A and suitably supported, as on a flange, a . As in the hydrant shown on Sheet 1 of the drawings, so here the cap is provided with a suitable handle, as a' , for enabling the cap to be turned. Two spiral or inclined actuating-slots, as E of Fig. 1, are also present in the cap, being located in the side of the latter and opposite to one another. In each of these slots is a projection or arm, d , firmly fixed to the discharge-pipe by suitable means—as, for example, by a collar, P . Rotation of the cap in one direction causes the slots E to elevate the arms d , and thereby lift the discharge-pipe and close the valve, the discharge-pipe sliding through the opening M in the top of the cap, 100 said opening likewise acting as a guide for the said pipe. All rotation of the discharge-pipe is prevented by means of the vertical slots D , heretofore described in connection with Fig. 1. One of the arms d passes through one of the 105 slots D , and the other of said arms passes through the other of said slots, and the latter allow of the arms d being elevated or lowered, but prevent lateral movement of the arms, and consequently prevent rotation of the discharge-pipe. Rotation of the cap in a reverse direction depresses the discharge-pipe and opens 110 the valve.

The pin B , affixed to the cap, (see Fig. 2,) is present in the slot b of the standard shown 115 in Fig. 5, and the cap, while allowed to rotate, is prevented from being raised from the stand-

ard until said pin is removed, when the cap may be removed and the discharge pipe and valve be lifted out of the standard.

In both the hydrant-heads shown, it will be observed that, except when taken off for repairs or to withdraw the discharge pipe and valve, the cap is rotatable upon, but is otherwise stationary with the standard; hence it does not rise nor fall under the hand while being turned, and the operator is relieved from the unpleasant compound movement which would occur if the cap not only turned but moved with the discharge-pipe while reciprocating the latter.

15 As before described, the projection for engaging the cap may be the spout or other projection from the discharge-pipe.

While the various features of my invention are preferably employed together, one or more 20 of such features are, so far as applicable, to be applied to hydraulic devices of other construction than such as herein shown.

Having thus described my invention, what I claim as new, and desire to secure by Letters 25 Patent, is as follows:

1. The hollow reciprocating piston - valve provided with central chamber, Z , communicating with the discharge - pipe, and having an imperforate bottom and packing-rings $h h'$, 30 and provided with orifices l , located in the side of the said valve between said packing-rings, and being the only inlet-conduits to said central chamber, Z , in combination with the valve-box having constricted portion f^2 , provided 35 below with the inlet-conduit, so that when the valve is moved vertically in one direction communication is made between the inlet-conduit and orifices l , and when the valve is moved in the opposite direction, communication 40 between said inlet-conduit and said orifices l is cut off, substantially as and for the purposes specified.

2. The combination of the valve - chamber having a constricted portion, f^2 , and an enlarged portion above provided with waste-orifice, and an enlarged portion below provided with supply-conduit, and the vertically-reciprocating piston-valve having an imperforate bottom and packing-rings $h h'$, and orifices located between the said packing-rings, so that when the valve is at the upper part 50 of its movement the upper packing shall be at a distance above the constricted portion, and the lower packing engaging the latter, and when the valve is at the lower portion of

its movement the lower ring shall be at a distance below the constricted portion, and the upper ring shall engage the latter, substantially as and for the purposes specified.

3. The combination of the valve-chamber 60 having a constricted portion, f^2 , and an enlarged portion above provided with waste-orifice, and an enlarged portion below provided with supply-conduit, with the vertically-reciprocating piston-valve having an imperforate bottom and packing - rings $h h'$, and orifices located between the said packing-rings, so that when the valve is at the upper part of its movement the upper packing shall be at a distance above the constricted portion, and 65 the lower packing engaging the latter, and when the valve is at the lower portion of its movement the lower ring shall be at a distance below the constricted portion, and the upper ring shall engage the latter, and the 70 ring n , for engaging upon the descent of the valve the flared portion f of the upper enlarged portion of the valve - chamber, substantially as and for the purposes specified.

4. In a hydrant, the rotatable cap A' , connected to the top of the standard and incapable of vertical movement, and provided with an inclined slot, E , receiving the non-rotatable spout connected to the vertical discharge-pipe, capable of vertical movement by means of the rotation of the cap, and the inclined slot E , substantially as and for the purposes specified. 80

5. The body A , provided with surrounding collar a and vertical slots $D D'$ and horizontal slots b , in combination with the cap A' , 90 provided with inclined slot E and pins B , and the spout C' , substantially as and for the purposes specified.

6. The body A , provided with slots $D D'$, in combination with the spout C' , provided with 95 lug d , and guiding-flanges $e e'$, fitting against the interior of the body, and means, substantially as described, for raising and lowering the spout and its connections, substantially as and for the purposes specified. 100

7. The combination of the cap rotatable upon (but incapable of vertical movement on) the standard, and having inclined slot E , with the reciprocating discharge-pipe provided with a projection engaging said slot, substantially 105 as and for the purposes specified.

BENJAMIN C. VANDUZEN.
